WASHING MACHINES

Peter Alexander Kleefisch, Hildesheim, Germany, assignor to Senkingwerk, Hildesheim, Germany, a German partnership

Filed June 23, 1965, Ser. No. 466,278

Claims priority, application Germany, June 27, 1964, S 91,738; Mar. 23, 1965, S 96,127
8 Claims. (Cl. 68—58)

The invention relates to a washing machine with a rotary washing drum open at both ends and divided by baffles into individual treatment zones.

Washing machines having an unperforated drum open at both ends have already been proposed. Within this drum is fitted a member with a helical surface, extending the full length of the various treatment zones, such as the individual washing and rinsing zones, to convey the wash through the drum. The disadvantage of such washing machines is that they cannot be run at will alternately in different directions, because, the movement of the wash to right or left being too great, one or two turns must be left free of wash at the beginning and end of the washing drum. Moreover, because of the relatively high pitch of the turns in the helix, the discharge of the wash is not continuous. In addition to this, the individual baths of liquid cannot be separated, because of the turns in the helix and the rotary motion of the washing drum. In washing machines of this proposed kind, the washing and rinsing compartments are partitioned off by helical plates or the spaces between them, but the various baths of liquid run into one another.

There have also been proposed washing machines in which the wash is kept on the move by virtue of the sloping position of the drum. Baffles are provided within the washing drum for the purpose of separating the individual treatment zones from one another. Experiment has shown that these baffles cannot be relied on to keep the individual baths apart according to temperature and concentration. The reason for this is that, as the wash being passed through the washing drum is carried along, the processing liquid also flows with it from one treatment zone to the next, so that satisfactory separation of the baths is not assured.

The purpose of the invention is not only to ensure satisfactory transference of the wash from one treatment zone to the other, but also to prevent the processing liquid from flowing across as this takes place.

Another feature is that the washing drum runs horizontally.

Two embodiments of a washing machine in accordance with the invention will now be described by way of example, with reference to the accompanying diagrammatic drawings, in which:

FIG. 1 is a longitudinal section and partial side elevation of a washing machine conforming to the invention, with separating rings of one proposed design;

FIG. 2 is an end elevation of the machine of FIG. 1;

FIG. 3 is a vertical section on the line III—III of FIG. 1;

FIG. 4 is a partial vertical section to an enlarged scale, of a washing machine in accordance with the invention, showing separating rings of a second embodiment;

FIG. 5 is a front elevation of a separating ring such as shown in FIG. 4; and

FIG. 6 is a plan view of the machine of FIG. 5.

Referring now to the drawings and in particular to FIGS. 1 to 3, a rotary washing drum 1 has openings 2 and 3, at its ends. The wash 4, is fed into the washing drum 1 through the opening 2 and discharged after treatment through the opening 3. The drum 1 is carried by rollers 5 which engage in a rigidly attached guide ring 6.

2

The drum 1 may be provided with a V-belt drive, for example, V-belts 7 being carried at one end around a friction surface 8 of the drum and at the other end around a driving roller, which, for the sake of simplicity, is not shown in the drawing.

The drum 1 is divided into individual treatment zones 9 to 12, of which 9 is the preliminary washing bath, 10 the final washing bath, 11 the preliminary rinsing bath and 12 the final rinsing bath. These individual treatment zones 9 to 12 are separated by self-contained (that is to say endless) separating rings 13, which form casings perforated at 14 and 15. The drawing shows clearly that perforations 15 are situated in the periphery of the end portion of each treatment zone 9 to 12, whereas perforations 14 are situated in the adjacent horizontal peripheral face of separating rings 13. Annular stepped portions 13a are disposed adjacent the outlet from each separating ring 13. This arrangement ensures that the wash 4 is not hindered in its passage through drum 1 and that the liquids in each of the treatment zones 9 to 12 are kept separated according to their temperatures and concentrations. The liquid carried along with the wash 4 as this passes on into the next treatment zone is diverted through perforations 14 and 15 back to its proper zone. Thus, the transference of liquid into the adjacent treatment zone is substantially prevented and the liquid level in each bath is maintained constant.

The washing drum 1 also carries rings of perforations at 15, so that, given a continuous feed, the same amount of water is collected in containers 16 and fed back from there into drum 1.

The wash 4 is fed forward or back by guide ribs 17 (FIGS. 1 and 3). These lie opposite one another, are inclined to the horizontal plane and slope upwards towards discharge opening 3. Owing to the slope on the guide ribs 17, an axial thrust to left or right, according to the sense of rotation, is exerted at every revolution and ensures that wash 4 is kept moving through drum 1. The provision of these guide ribs 17 has made it possible for the first time to make washing machines without continuous helices and without sloping the drum, in which the wash 4 can be satisfactorily conveyed through the entire length of the drum without any auxiliary aids.

To ensure that the wash 4 remains in the washing drum 1 for a given period, the direction of rotation of the drum is changed periodically. Thus, for example, the washing drum 1 may make 4 revolutions anti-clockwise and 3 revolutions clockwise. The extra anti-clockwise revolution has the effect of producing a constant feed towards the discharge opening 3, so that the cleaned wash 4 can be discharged continuously.

The various baths in treatment zones 9 to 12 are kept supplied through openings 19 in a feed pipe 18, which passes through the interior of the washing drum 1. This feed pipe 18 may well be divided into two parts by a separator 18a. The part shown on the left of the drawing serves to supply fresh water for the rinsing baths, whereas the right-hand half is suitable for the supply of hot water and detergent mixture.

In the embodiment shown in FIGS. 4 to 6, separating rings 20 are in the form of a flat-faced helix with a single turn, the space between the two ends of the helical face being bridged across by a casing 21, containing perforations 22 and 23. These perforations 22 and 23 are provided in side 21a of the casing 21, which faces towards the treatment zone concerned, and in the adjacent face 21b of the casing, which runs horizontally. Adjoining this face 21b is a sloping face 21c. As the washing drum 1 rotates, the wash 4 is lifted up and moves over the faces 21c and 21b into the position numbered 4'.

This special design enables washing drum 1 to be run empty, the movement of wash 4 not being hindered by in-

terruption of thrust. Moreover, with the embodiment illustrated in FIGS. 4 to 6, too, guide ribs 17 are provided, though these have not been shown in the drawing, for the sake of simplicity.

The scope of the invention also covers the possibility 5 of making the separating rings 20 in the form of relatively thin-walled separating discs.

I claim:

1. In a washing machine, a rotary washing drum having open ends, and baffle 10 means within the drum defining individual treatment zones, said baffle means comprising, hollow rings each being formed with openings such that liquid in a given zone is returned to that zone through the openings if the liquid is carried into the hollow 15 ring downstream of that zone.
2. In a washing machine, a rotary washing drum having open ends, drive means coupled to the drum, and a plurality of spaced hollow rings mounted within the 20 drum and serving to divide the drum lengthwise into a plurality of individual treatment zones, each ring including a pair of walls lying in radial planes and a cylindrical wall co-axial with the drum, the cylindrical wall and the part of the drum bounding each 25 ring being provided with openings, said opening serving to drain any liquid of a given treatment zone which is conveyed out of that zone towards the next adjacent zone.
3. In a washing machine, 30 a rotary washing drum, a plurality of hollow helical baffles mounted at spaced intervals within the drum, the intervals defining separate treatment zones and each baffle extending through substantially one complete turn, and an apertured casing means spanning the ends of each baffle, the arrangement being such that liquid in any given zone carried in the direction of the next adjacent downstream zone passes through the said apertures and is returned to the said given zone. 40
4. In a washing machine according to claim 3, a wall of the casing extending in the axial direction of the drum, and a wall of the casing lying in a radial plane, both said walls having apertures therein. 45
5. In a washing machine, a rotary washing drum, a plurality of baffles mounted within the drum and defining a plurality of individual treatment zones, and guide ribs inclined with respect to the axis and mounted within the drum in each zone thereof, said guide ribs serving to advance wash material through the drum, each of said baffles being formed with openings such that liquid in any given zone is returned to that zone through the openings if the liquid is carried into the baffles downstream of that zone. 50
6. In a washing machine, a horizontally-extending drum having open ends, and baffle means mounted within the drum and defining individual treatment zones, each baffle means being formed with openings such that liquid in any given zone is returned to that zone through the openings if the liquid is carried into the baffle means downstream of that zone. 60
7. In a washing machine,

a rotary horizontally-extending elongate washing drum having open ends for the introduction and removal of wash material, means defining two annular guide tracks mounted on the exterior of the drum, a plurality of rotatably mounted rollers engaged in each guide track, mounting means for each said roller, drive means coupled to rotate the drum, a plurality of spaced hollow baffle rings rigidly mounted within the drum, adjacent baffle rings defining individual wash-treatment zones, a plurality of inclined ribs secured to the inside face of the drum for forwarding wash material through the drum, pipe means introducing wash treatment liquid into the individual zones, and trough means disposed below each baffle ring externally of the drum, the baffle rings and parts of the drum surrounding the baffle rings having openings for the passage of liquid from that zone upstream of a given one of the baffle rings which has been carried over by wash material to the trough means.

8. In a washing machine, a rotary horizontally-extending elongate washing drum having open ends for the introduction and removal of wash material, means defining two annular guide tracks mounted on the exterior of the drum, a plurality of rotatably mounted rollers engaged in each guide track, mounting means for each said roller, drive means coupled to rotate the drum, a plurality of spaced hollow helical baffles rigidly mounted within the drum, adjacent baffles defining individual wash-treatment zones, and each baffle extending through substantially 360° between the ends thereof, casing means extending between the ends of each baffle, said baffles and casing means having apertures therein through which liquid from a given treatment zone entrained by wash material passing over the baffle and the casing means on the way to the next adjacent zone downstream can be returned to said given treatment zone, a plurality of ribs secured to the interior face of the drum forwarding wash material through the drum, and pipe means introducing wash treatment liquid into the individual zones.
